UNITED STATES PATENT OFFICE.

WITT JUNIPER, OF BERWYN, ILLINOIS, ASSIGNOR, BY DIRECT AND MESNE ASSIGNMENTS, TO GITS ELECTRICAL COMPANY, OF FRANKLIN PARK, ILLINOIS, A CORPORATION OF ILLINOIS.

ELECTRIC IRON.

1,203,004.

Specification of Letters Patent. Patented Oct. 31, 1916.

Application filed October 30, 1915. Serial No. 58,792.

To all whom it may concern:

Be it known that I, WITT JUNIPER, a citizen of the United States, residing at Berwyn, in the county of Cook, State of Illinois, 5 have invented certain new and useful Improvements in Electric Irons, of which the following is a specification, reference being had to the accompanying drawings.

My invention relates to electric irons and 10 it has for its principal object the provision of a new and improved form and arrangement of parts by reason of which the iron can readily be taken apart and again properly assembled by any ordinary user of the 15 iron of very little or no mechanical skill, and by the use of a very limited tool equipment.

To this end it is one of the objects of my 20 invention to provide contacts or binding posts for the heat unit of the iron arranged in such a way that they offer no obstacle to the free separation of the parts of the iron.

It is another object of my invention to 25 provide for the proper protection of the heat unit such that the unit can be taken from the iron and sent through the mails for repair without undue danger of injury to the unit, the arrangement of the protecting parts being such that the proper directing 30 of the heat to the sole of the iron is not interfered with.

It is another object of my invention to 35 provide a construction in which a maximum protection is afforded guarding against the escape of the heat through the upper part of the iron away from the sole.

It is another object of my invention to 40 improve devices of this type in sundry details hereinafter pointed out.

45 The preferred means by which I have accomplished my several objects are illustrated in the accompanying drawings and are hereinafter specifically described.

That which I believe to be new is set forth 50 in the claims.

In the drawings, Figure 1 is a side view 55 of an iron embodying my improved construction; Fig. 2 is a transverse vertical section through the body of the iron, being taken substantially on line 2—2 of Fig. 1; Fig. 3 is a longitudinal vertical section through the center of the body of the iron, being taken substantially on line 3—3 of Fig. 2; Fig. 4 is a top plan view of the heat unit of my iron; Fig. 5 is a vertical cross-

section through the heat unit, being taken substantially on line 5—5 of Fig. 4; and Figs. 6 and 7 are detailed views showing the elements of the connections between the binding posts and the heat unit. 60

Referring to the several figures of the drawings in which corresponding parts are indicated by the same reference characters, 10 indicates the top or shell of the iron secured by means of screws 11 to the sole 12 65 of the iron, the shell 10 being in contact with the sole only at its lower edges, as shown in Figs. 2 and 3. A handle 13 is secured upon the top or shell 10 by means of the screws 11, washers 14 being interposed between the top 10 and the strap 15 of the handle 13 for insulating the handle from the body of the iron. 70

The heat unit 16 of the iron rests upon the sole 12, being held in position thereon by a 75 pressure-plate 17 which is secured upon the sole 12 by means of a screw 18. The pressure-plate 17 serves to press the flexible heat unit 16 firmly down upon the sole 12 and also serves for storing heat within the body 80 of the iron. As is best shown in Figs. 2 and 3, the pressure-plate 17 is separated by an air space on all sides from the top or shell 10 of the iron so as to prevent very largely 85 the escape of heat from the pressure-plate 17 to the shell 10. The pressure-plate 17 is preferably in the form of a casting having the scale removed from the bottom face only, the scale remaining on the upper and outer 90 faces of the plate, being of assistance in retaining the heat in the plate. 95

The heat unit 16 comprises a plate 19 having a considerable length of resistance wire 20 wound thereon. In the construction shown, the resistance wire 20 is made in the form of a narrow flat strip, being formed of any suitable material. Plates 21 and 22 are secured in position on the upper and lower faces of the plate 19 with the wire 20 wound thereon. As will be readily understood, the plates 19, 21 and 22 are to be formed of a suitable insulating material, being preferably plates of mica. For the protection of the mica plates of the heat unit when such unit is to be taken out of the iron, metal plates 23—24 are provided on the upper and lower faces respectively of the unit. The plate 24 is preferably to be made of brass, which is a very good conductor of heat, by which the passage of the 100 105 110 115 120

heat from the unit to the sole 12 will be favored, while the plate 23 is to be made of iron or some other metal which is a comparatively poorer conductor of heat than brass. In the construction shown, the plates 23—24 are bound together by tongues 25 cut from the plate 24 extending through suitable slots 26 in the plate 23. At the ends of the unit the plate 24 is turned about the 10 end of the plate 23, as best shown in Figs. 3 and 4.

The ends of the wire 20 are connected to contacts 27 and 28, respectively, which are fixed upon the unit 16 in any suitable manner. The binding posts 29 by which the heat unit is adapted to be connected with any suitable source of electrical energy are fixedly mounted upon the shell 10 directly over the contacts 27—28, as best shown in 15 Fig. 3, such binding posts being insulated by means of mica or in any other suitable manner from the shell 10. Fixed upon the lower end of each of the two binding posts 29, preferably by means of a nut on the 20 lower end of the binding post, is an arm 30 provided at its lower end with a flattened sleeve or housing 31 adapted to slip readily over the upwardly-extending end of one of the contacts 27—28. By this means the 25 binding posts 29 are suitably connected with the ends of the resistance wire 20. At the same time upon the removal of the screws 11 the top or shell 10 of the iron with the binding posts 29 mounted thereon is adapt- 30 ed to be lifted freely out of contact with the sole 12 without the loosening of any part or parts. Upon the subsequent removal of the screw 18, the unit 16 is freed from the sole 12 and is in condition for carriage by mail 35 or otherwise without undue danger of damage to the mica plates 19, 21 and 22. As is best shown in Fig. 3, the plate 23 is turned upward at one end for supporting a plate of mica 32 between the pressure-plate 17 40 and the contacts 27—28 for securing the proper insulation between such parts.

The sole 12 is preferably nickelized upon its entire surface except the upper face with which the brass plate 24 is brought in contact. This upper face of the sole 12 is preferably free of nickel which is a comparatively poor conductor of heat. In case the sole 12 is cast out of iron, the upper face is 50 preferably machine finished for the removal of the scale so as to facilitate the passage of the heat from the unit 16 into the sole.

The sole 12 and the shell 10 are preferably pointed at both ends to conform to the shape of the heat unit 16 as shown in Fig. 4, although I do not wish to be restricted to 60 this form except as hereinafter specifically claimed.

By the use of a plate 23 of comparatively poor heat-conducting qualities on one face of my heat unit and the use of a plate 24 of comparatively much better heat-conducting qualities on the other face, I have provided a construction by which the heat produced is directed largely toward such plate 24. So far as I am aware, I am the first to 70 produce a heat unit of this type, and my claims are to be construed accordingly.

What I claim as my invention and desire to secure by Letters Patent, is—

1. An electric heating unit comprising in 75 combination an electric circuit member of resistance material, a brass protecting-plate insulated from said resistance member on one face thereof, and an iron protecting-plate insulated from said resistance member 80 on its opposite face.

2. An electric heating unit comprising an 85 electric circuit member of resistance material, metal face-plates secured on opposite sides of said electric circuit member, and insulating means between said circuit member and said metal plates, the metal plate forming one face of the unit being of a metal of higher heat conductivity than that of the other plate.

3. An electric heating unit comprising a 90 sheet of mica, a resistance coil wound thereon, sheets of mica on opposite faces of the resistance coil, and metal face-plates secured on opposite faces of said second-named 95 sheets of mica respectively, one of said face-plates being formed of a metal of higher heat conductivity than that of the metal forming the other face-plate.

4. An electric heating unit comprising a 100 sheet of mica, a resistance coil wound thereon, sheets of mica on opposite faces of the resistance coil, and metal face-plates secured on opposite faces of said second-named 105 sheets of mica respectively, said metal face-plates being held rigidly in position relative to each other by tongues formed with one of said face-plates extending through openings through said sheets of mica into engagement with suitable openings in the other face-plate.

WITT JUNIPER.
